United States Patent

Des. 236,665
Patented Sept. 9, 1975

236,665

BOOT

Guy De Massacr , Paris, France, assignor to
Hutchinson-Mapa, Paris, France

Filed Nov. 7, 1973, Ser. No. 413,679

Claims priority, application France May 28, 1973

Term of patent 3½ years

Int. Cl. D2—04

U.S. Cl. D2—275

FIG. 1 is a side elevational view of a boot showing my new design;

FIG. 2 is an elevational view of the other side of the boot;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a boot, substantially as shown and described.
